VIBRATOR

Hugo Benioff, Pasadena, Calif., assignor to Submarine Signal Company, Boston, Mass., a corporation of Maine

Application March 31, 1944, Serial No. 529,018

7 Claims. (Cl. 172—126)

1

The present invention relates to a vibrator designed to produce mechanical vibrations for controlling electrical circuits to produce alternating or pulsating currents. The aim of the device of the present invention is to provide reliable vibrating electric contacts for converting direct current into pulsating or alternating current in a range approximately from 20 to 1,000 cycles. A characteristic of the present invention is that the vibrator is of the ribbon type and is operated preferably as a duplex half wave ribbon vibrator with contact points common to the two segments with separate contacts for driving and for operating an external circuit or circuits. The points are positioned at the center of the ribbon which is a quasi node for both vibrating sections. The fixed contact screws limit the ribbon amplitude at this point to small values and thus establish a quasi or approximate node.

This and other features of the present invention will be more thoroughly understood when considered in connection with the drawings illustrating an embodiment of the same in which Fig. 1 shows the invention in elevation with parts shown in fragmentary section; Fig. 2 shows a top plan view of the invention looking down upon the view of Fig. 1; Fig. 3 shows a bottom plan view of the invention looking up from the bottom of Fig. 1; Fig. 4 shows a section taken substantially upon the line 4—4 of Fig. 1; Fig. 5 shows a section taken substantially upon the line 5—5 of Fig. 1; Fig. 6 shows an end view as viewed from the right end of Fig. 1; Fig. 7 shows a circuit diagram showing the control circuit for operating the vibrator and also the control of the electrical circuit obtained through the motion of the vibratory ribbon; Fig. 8 shows a section taken on the line 8—8 of Fig. 1 and Fig. 9 shows a mode of vibration which the vibrator may undergo.

In the drawings the device comprises a heavy base member 1 which is elongated and serves as a spanning support over which a ribbon 2 is placed and held taut at both ends of the base by clamping members or plates 6 and 7. The clamping plate 1 clamps directly to an upwardly extending end portion 4 of the base while the clamping plate 6 clamps to an adjustable support 3 which may be adjusted in a longitudinal direction with reference to the ribbon so as to obtain the desired tension. For this purpose the end support 3 is provided with a top clamping block 8 and two recess channels 9 and 10 in its side faces, which recess channels receive forked extensions 11 and 12 of the base 1. A machine stud or bolt 13 passes through these forked ends 11 and 12

2

and through an elongated slot 12' elongated in the direction of the ribbon and longitudinally with the base in the stem portion of the block 3. An adjustment screw 14 passes through the block 3 of the support 3 from the end working against the end of the base 1. In adjusting for the desired tension on the ribbon 2 this adjustment screw 14 is turned until the desired tension is obtained on the ribbon and the nut 13 may be tightened clamping the block rigidly in place. The frequency of the vibrator may be adjusted in this way.

The ribbon 2 is vibrated electromagnetically by means of two spaced armatures 15 and 16. These armatures comprise a top clamping plate or block 17 and a lower member 18. These two members 17 and 18 are positioned one on either side of the ribbon and are clamped to the ribbon and to each other through the clamping screws 19. The lower block 18 is recessed to receive a stack of armature laminations 20 which are held within the recess of the holder 18 by means of a pair of screws 21 which pass through holes in the side of the holder 18. The outer corner faces of the laminations 20 come normally in proximity to the pole members 22 and 23. These are poles of the electromagnet 24 which is made up of a stack of U-shaped laminations 25 which have energizing coils 26 and 27 placed upon each of the pole elements. This structure is duplicated in both halves of the apparatus. The laminations 25 are held in place by means of a clamping plate 28 which is held to the side of the base 1 by the screws 29. The electromagnet with its exciting coils are set in a recess in the base 1, which recess is made to receive snugly the laminations and permit the coils to fit over the pole arms. The structure is further held in place by means of clamping brackets 29 and 30 which are provided with shoulders extending over the upper outer corners of the laminations. The brackets 29 are clamped to the base 1 by means of screws 31 while the brackets 30 are joined together by a central element 32 which is bolted to the base by means of screws 33 and 34. The electromagnet structure, therefore, is rigidly assembled in the base but may be removed for changing of the coils or for any other purpose.

The armature laminations attached to the ribbon are not limited in their transverse motion since the armature laminations clear the poles 22 and 23 and dip between them in the vibratory motion of the ribbon.

The manner in which contacts between the ribbon contact points and the stationary contact

screws resulting from vibration of the ribbon operate, will now be described. These contacts are positioned substantially halfway between the clamping ends 6 and 7 and are likewise substantially the same distance from the two armatures on the ribbon.

Attached to the base 1 midway between the ends are two side brackets 40 and 41 which are held to the base through side screws 42 and 43, respectively. These brackets 40 and 41 have shoulders formed from the inner side of the bracket outward recessed into the bracket as indicated at 44. Positioned in this recessed shoulder on one side is the contact holder or support 60 which is held to the bracket by means of a screw 46 passing through the wall of the bracket and entering into the end of the holder 60. The holder 60 is tapped to receive the contact screw 52 which may be adjusted vertically, as indicated in Fig. 4, with reference to the ribbon 2 on which the opposing contact points 59 and 58 on one side and 57 and 56 on the other side are rigidly fixed by welding, soldering or any other desired means. The contact screw 52 is adjustable up and down for the desired position and for this purpose the member 32 is recessed to prevent electrical contact therewith if desired. As indicated in Fig. 4 the contact screw 52 is not insulated from the supporting bracket 40 although this may be done if desired, as is the case of the other holder or support 61. This is supported by means of the screw 47 and the member 60 rests in a shield 45 which separates the holder 61 from the bracket 41. The contact screw 53 is adjustable in the holder 61. When proper adjustment has been obtained, the clamping screws 62 and 63 may be tightened for tightening the split tap in which the contact studs 52 and 53 thread. While this construction is not shown in the drawings, it is the same as the construction for the holders of the top contact members 54 and 55 which are supported in the holders 48 and 49 clamped by means of screws 50 and 51 to the top surface of the brackets 40 and 41. These holders 48 and 49, as indicated in Fig. 2, are tapped to receive the contact stud screws 54 and 55. The holders 48 and 49 are slotted as indicated at 64 and 65, the slots extending from the tapped holes for the studs 54 and 55 to small recesses or holes in the pieces 48 and 49 in the same direction as the taps. The screws 57 and 58 entering the members 48 and 49, respectively, from the sides tighten the studs in the taps after these have been set in proper positions. The contacts 56 and 58 and 57 and 59 are shaped to have a bevelled or knife edge running transverse to the longitudinal direction of the ribbon, thus fixing the length of the ribbon from the clamping point to the point of vibrational contact.

The electrical energizing system which may be employed is indicated in Fig. 7. Corresponding to elements in Fig. 1 the circuit of Fig. 7 comprises four coils 26, 26, 27, 27 across which a condenser 70 may be placed for tuning or partially tuning the electrical circuit to the frequencies of the mechanical vibrations of the ribbon.

The condenser and coils may be attuned to a harmonic or a multiple of a half harmonic such that the contacts of the vibrator will open at instants when the current across the contacts is substantially zero. That is to say, the oscillations of the condenser circuit should be such that the current across the contacts is zero at the instant that the contacts are opened. This, of course, refers to the steady-state condition

which is reached after the first few vibrations of the ribbon. The contacts may also be shunted by condensers 71 and 72 and the energy may be supplied from a battery source 73 or any other electrical potential which may, in fact, be either direct or alternating current. As indicated in Fig. 7 one stud contact which may be assumed as 53 is completing the circuit of the contact 57 on the ribbon while the other stud contacts 52 and 54 are positioned to the ribbon contacts 56 and 58. Contacts 57 and 53 open and close the circuit to the electromagnets whereby periodic traction on the two ribbon armatures is effected. The contacts 52 and 54 work with the contacts 58 and 56 to supply energy to the load 74. This double contact system for the load 74 provides that contact frequency is supplied at double the vibration frequency of the ribbon.

Fig. 9 illustrates the mode of vibration of the ribbon where both sets of electromagnets are simultaneously energized in a manner in accordance with the circuit of Fig. 7. This motion is a forced vibration in which a quasi node exists at the midpoint of the ribbon. Since each set of electromagnets simultaneously pulls the armatures on the ribbons in synchronous motion, a vibration is built up with the maximum amplitude occurring at the place of the armatures and the minimum amplitude with the greatest transverse force occurring at the point of contact. The ribbon frequency is determined by the mechanical constants of the ribbon such, for instance, as its length, its tension and the manner in which it is weighted. For general purpose the string or ribbon vibrator may be called a "loaded duplex" ribbon vibrator.

The contacts 56 and 58, Fig. 9, while moving with only a small amplitude, nevertheless move with considerable force and therefore provide reliable and positive contacts at the points.

Having now described my invention, I claim:

1. A vibrator of the type described comprising a ribbon, electrical means for driving said ribbon at a plurality of spaced points thereon, and electrical contact means positioned some on the ribbon and some fixed in opposing position thereto between the points of drive for controlling the energization of said drive.

2. A vibrator of the type described comprising a ribbon, electrical energizing means for driving said ribbon in symmetrical duplex fashion with a quasi node on the ribbon between the points of drive and means making electrical contact for controlling said energizing means positioned at said node.

3. A vibrator of the type described comprising a ribbon, means stretching said ribbon between its ends, contact means positioned substantially midway between the ends thereof, and energizing means periodically operated by said contact means positioned to act on said ribbon between the ends thereof and the position of said contact means.

4. A vibrator of the type described comprising a base member having clamping means at either end thereof, a ribbon element having magnetizable armatures suspended between said clamping ends over said base, electromagnetic means positioned on said base and operatively associated with said armatures for vibrating the ribbon and a plurality of contact members mounted on said base and cooperating with contact members mounted on said ribbon for opening and closing a circuit to said electromagnetic means, and

means supported on said base for adjusting the tension on said ribbon.

5. A vibrator of the type described comprising a ribbon element having magnetizable means, means suspending said ribbon element tautly between its ends, electromagnetic means supported by said suspending means, and operatively positioned with regard to said magnetizable means, contact means operatively associated with said ribbon element for opening and closing an electric circuit to said electromagnetic means, and means mounting part of said contact means in a fixed position relative to said ribbon element.

6. A vibrator of the type described comprising an elongated base member having clamping means at either end thereof, a ribbon element suspended between said clamping ends of said

base, electromagnetic means operatively associated with said ribbon element and contact means having elements mounted on said ribbon and elements suspended from said base adapted to open and close an electric circuit to said electromagnetic means.

7. A vibrator of the type described comprising a vibratory ribbon, electromagnetic means for driving said ribbon, electrical contact means adapted to be opened and closed by vibration of said ribbon for controlling the energization of said electromagnetic means, and means in circuit with said electromagnetic means for tuning the same to produce substantially zero current across said contact means at the instant of opening.

HUGO BENIOFF.
